UNITED STATES PATENT OFFICE.

JULIUS E. WATEROUS, OF BRANTFORD, CANADA.

VALVE FOR STEAM-ENGINES.

SPECIFICATION forming part of Letters Patent No. 449,504, dated March 31, 1891.

Application filed May 16, 1890. Serial No. 352,111. (No model.)

To all whom it may concern:

Be it known that I, JULIUS E. WATEROUS, a citizen of the Dominion of Canada, residing at Brantford, in the county of Brant, Province of Ontario, Canada, have invented a new and useful Improvement in the Arrangement of Valves for Steam-Engines, of which the following is a specification.

My invention relates to improvements in steam-engines in which two circular or rotary exhaust-valves are placed in separate steam and exhaust chests on the lower side of a steam-engine cylinder, as near the ends as possible, and two admission and cut-off valves of the piston type placed in one steam-chest on the side of the cylinder immediately above, and connected to and forming a part of the steam-chests containing the exhaust-valves; and the objects of my improvement are, first, to provide exhaust-valves, one at each end of the cylinder, with as short ports or passages into and from the cylinder as possible, and so arranged that when the steam in the cylinder has accomplished its work and is released it passes directly out into the exhaust-chamber through the opening under the valve, which at the same time prevents the remaining steam in the steam-chest from escaping, which would be the case if these valves and ports were not arranged in this way; second, to provide separate admission and cut-off valves arranged as stated above, and connected to the steam-chest containing the exhaust-valves and arranged in such a manner that when the steam is admitted by these valves it passes into the steam-chest of the exhaust-valves over the latter, directly into the port leading to the cylinder, these admission and cut-off valves being operated by an eccentric attached to the governor, they being entirely automatic in their operation; third, to provide an easy means of adjustment for the admission and cut-off valves, which are placed on and operated by one spindle, so that they can be readily set or their lead changed, as the case may require. I attain these objects by the mechanism illustrated in the accompanying drawings, in which—

Figure 1 is a side elevation of an engine-cylinder, showing the arrangement of valves in broken section. Fig. 2 is an end elevation of an engine-cylinder, showing the relative

position of the valves and the manner in which the steam-chests are connected. Fig. 3 is an enlarged sectional side elevation of the admission and cut-off valves with the bush which surrounds the same, showing the steam-inlet openings and spindle by which the valves are operated. Fig. 4 is an end elevation of the same.

Similar letters refer to similar parts throughout the several views.

The steam-cylinder A is of the usual form and provided with an ordinary piston and piston-rod, as shown at H, having the steam-chest C C, containing the admission and cut-off valves G G G G, spindle h, extension-nut e, and valve-bushes a a, placed on the side of the cylinder, as shown in the drawings. In this steam-chest there are four valves, two placed in each bush, and each having two openings or steam-passages d d, which correspond with those in the bushes, thus giving double openings to each end of the cylinder. These valves are connected and operated by one spindle h, which is connected to and controlled by an eccentric attached to the governor. Thus only sufficient steam is allowed to pass through these valves into the cylinder to keep the engine running at its proper speed. These valves are held in place by the collar f and the jam-nuts o, and are provided with an extension-nut e, which is fitted with a right and left hand thread, so that the valves may be extended or brought together, as the case may require. To give them the necessary lead and lap, openings for this purpose are provided in the outer case and are covered by caps I I. To prevent their leaking through wear the valves are provided with an expansion-ring, as shown at g, Fig. 3.

When the valves are opened, the steam passes into the lower steam-chest E, over the exhaust-valves F into the cylinder through the ports p. When the point of cut-off is reached by the piston, these valves are closed. This point is regulated by the governor, but is never allowed to go beyond three-quarter stroke, so that they are always closed before the exhaust takes place. When the piston has finished its stroke and the steam is to be released, it passes out of the cylinder through the port p and opening S under the exhaust-valve F, which while the exhaust is taking

place connects the steam-port *p* with the exhaust-port *J*, thus making one continuous opening leading from the cylinder to the exhaust-box *K*, where it finally escapes through 5 the opening *L*.

These exhaust-valves are driven by one eccentric attached to the engine-shaft, so that their motion is always a positive one, and the exhaust-ports *S* under the valves are so 10 arranged that they begin to open to release the steam from the cylinder from the steam side of the piston as the latter approaches the end of the stroke, while the opposite valve is made to close on the exhaust side of the piston, thus giving the latter the required cushion. 15

I am aware that prior to my invention circular or rotary valves, such as I have adopted for exhaust-valves, have been in use, and I do not claim them broadly; and I also know 20 that piston-valves have been in use before my invention; but I am not aware that hollow piston-valves, each having double openings, such as shown and described above, have ever been used as admission and cut-off 25 valves in combination with circular or rotary exhaust-valves. Therefore

What I claim as my invention, and desire to secure by Letters Patent, is—

1. The combination, in a steam-engine, of 30 two circular exhaust-valves *F F*, placed in separate steam-chests *E E*, one at each end of

the cylinder at right angles to its bore, with two admission and cut-off valves *G G* of the piston type contained in one steam-chest placed on the side of the cylinder immediately above and connected to and forming a part of the steam-chests containing the exhaust-valves, all substantially as set forth.

2. The combination of two hollow piston-valves *G G*, placed in one steam-chest *C* on 4 the side of an engine-cylinder, each having two ports or steam-passages *dd* with and leading directly into the steam-chests *E E*, containing the exhaust-valves *F F*, in such a manner that the inflowing steam passes through 4 the admission-valves into the steam-chests *E*, over the exhaust-valves *F*, and into the steam-port *p* on its way to the cylinder, substantially as described.

3. The combination of two admission and 5 cut-off valves *G G* in one steam-chest placed on and operated by one spindle *h*, and connected to each other with an extension-nut *e*, fitted to the stem of the valves by a right and left hand screw in such a way that the valves 5 can be extended or drawn together, as required, all substantially as set forth.

Brantford, May 13, 1890.
